UNITED STATES PATENT OFFICE

BUEL COUCH, OF SIOUX CITY, IOWA

ANIMAL TRAP

Application filed August 31, 1928. Serial No. 303,215.

My invention relates to animal traps of the type patented in my U. S. Patent No. 1,674,276, issued June 19, 1928, and has for its object to improve upon the construction 5 of that patent.

One object of my invention is to preserve the general features of construction of said patent, to wit; a treadle extending the full length of the trap, a sliding jaw, a plunger 10 shaft secured to the jaw and slidably mounted, and a compression spring encircling the shaft and engaging a fixed bearing to exert pressure against the sliding jaw; and to incorporate into this general arrangement, a 15 highly sensitive trigger arrangement.

One feature of the trigger construction which the present invention provides, is a greater treadle leverage, which is attained by employing an element in engagement with 20 the treadle in such a manner that a very slight amount of movement of the treadle is necessary to release it, and placing the point of engagement near to the hinge between treadle and base of the trap.

25 Another feature of the trigger mechanism which it is my object to attain in this invention, is an intermediate trigger to receive the direct pull of the sliding jaw, and to in turn be engaged and retained by the treadle.

30 My purpose in providing such an intermediate trigger, is to take a large proportion of the pull of the sliding jaw from the treadle, and transfer it to the trigger. The trigger is so arranged that it takes the direct pull of 35 the jaw at an angle, resolves it into two forces, one opposed by the trigger, and the other, much the smaller of the two, opposed by the treadle. These two forces act at substantially right angles to each other, and thus 40 the opposing force of the trigger can be exerted longitudinally of the sliding jaw shaft, with which the trigger makes contact, and transversely of the treadle, which is parallel to the shaft.

45 A further object of my invention is to improve upon the sliding engagement of the jaw and base of the trap.

Another object is to provide a trap which 50 may be set without engaging the treadle with the hands of the operator, the treadle being

adapted to spring into set position automatically, and the other parts being similarly arranged to assume their proper positions for setting the trap, without aid from the hand of the operator.

55 A still further object is to provide a convenient gripping arrangement whereby the hands of the operator may easily engage the sliding jaw and base of the trap in such a manner as to allow ready application 60 of pressure from the fingers to set the trap.

A further object is to provide a trap having the foregoing features, and, in addition, 65 simplicity, durability, and inexpensiveness of construction.

With these and other objects in view, my invention consists in the construction, arrangement, and combination of the various parts of my invention, whereby the objects contemplated are attained, as hereinafter 70 more fully set forth, pointed out in my claims, and illustrated in the accompanying drawings, in which,

Fig. 1 is a side elevation of the trap,

Fig. 2 is a plan view of the trap, sprung, 75

Fig. 3 is a plan view of the trap, set,

Fig. 4 is an end view of the trap, sprung, and

Fig. 5 is a sectional view of the sliding jaw.

80 One objection to the trap of my patent, hereinbefore referred to, arises from the distance to the hinge end of the treadle, from the point where the treadle engages the sliding jaw. Because of the small ratio of treadle length to this distance, the effective leverage of the treadle in springing the trap is small. In the present invention, a much higher ratio is obtained by the use of a trigger, provided 85 with a rearwardly extending arm to engage the treadle near its hinge, and sensitivity is further increased by taking a large proportion of the direct pull of the jaw from the treadle, and transferring it to the trigger, which is made self releasing from engagement 90 with the jaw, in the absence of the restraining force of the treadle against the trigger.

95 In the accompanying drawings, the base of the trap is shown at 10, constructed of a flat 100

slab of wood. The sides of the base are bevelled as shown in Fig. 4.

Secured to the base is the L-shaped member 11, forming the jaw 12 extending at right angles to the base 10, at one end thereof. The sliding jaw comprises a plate 13, slideable on the base 10, and provided with fingers 14, embracing the bevelled sides of the base.

A jaw proper 15 is formed by bending up the plate 13 at one end, and finger-engaging elements 16 are bent upwardly from the other end of the plate 13. The elements 16 are provided with guards 17, which prevent the fingers of the operator from engaging the spring and treadle, received between the finger engaging elements.

The treadle 18 is formed of a flat strip of sheet metal, perforated at 19 to receive a pin 20, to secure it to the base 10. The pin 20 is loose enough in its engagement of the treadle to allow the latter to freely hinge relative to the base.

A light spring 21 urges the treadle upwardly.

A strip of wood or fibre 22 is secured to the end of the treadle which will be exposed to the tread of an animal.

A bridge-shaped bracket 23 is secured to the base 10 just far enough from the jaw 12 to allow the sliding jaw to be moved away from the jaw 12 to provide a runway for mice, or whatever animal the trap is built for. It will be understood that I do not intend to limit the use of the trap to mice, as it will be equally effective for rats, when built in larger proportion, and may be used for other animals as well.

An ear 24 projects upwardly from that side of the bracket 23 which is toward the jaw 12, and is provided with an opening forming a bearing for the shaft 25, secured to the jaw 15, parallel to its path of movement.

A compression coil spring 26 encircles the shaft 25, between the jaw 15 and the ear 24, and serves to urge the jaw 15 toward the jaw 12.

It may be noted at this point that the treadle 18 and the spring 26 and shaft 25 extend through the space between the guards 17, the latter serving to prevent contact of the operator's fingers with the former, and providing a guide bearing surface for the edges of the treadle.

The treadle is held in position centered between the sides of the base, by the side extremities of an opening 27 in the sliding jaw 15 (Fig. 5). The treadle is of such length as to extend into the opening even when the trap is sprung, so that the end of the treadle may not catch against the jaw 15.

The shaft 25 is provided with a detent 28 in one side. A trigger 29 is pivoted at 30 to the bracket 23, and is provided with a lug 31, extending upwardly to engage the side of the shaft 25. When the sliding jaw has

been opened to the extent of its movement, the detent 28 will register with the lug 31, and one of the finger engaging elements 16 will engage a lateral arm 32^a on the trigger 29, forcing the trigger to swing about its pivot, and moving the lug 31 into the detent 28. This is one feature of the self-setting arrangement.

It will be understood that in Fig. 3 of the drawings the trap is shown with its parts positioned after setting of the trap. The movement of the finger engaging element 16 toward the trigger during the setting operation will exceed the position shown in Fig. 3, to which position it will recede after the trigger has caught and the various parts have been pulled taut under the pressure of the spring.

The lug 31 is positioned, relative to the pivot 30, on a line which intersects the shaft 25 at an acute angle. Consequently, the pull of the shaft 25 against the trigger, will be resolved into two forces, one parallel to the shaft, and the other transverse thereto. The former will be the larger force, the latter being only a small proportion of the total, due to the acuteness of the angle at which the pull is received.

It will now be noted that the more acute the angle of pull, the smaller will be the lateral resultant of force. To be more specific, the nearer parallel the line connecting the lug 31 and the pivot 30, to the axis of the shaft 25, the greater will be the percentage of pull borne by the trigger. The lateral resultant may thus be adjusted by adjusting the pivot nearer to the center of the shaft, or vice versa.

This lateral resultant of force is opposed by the treadle, the trigger being provided with a depending lug 32, which rests against the upper surface of the treadle when the trap is sprung, and is adapted to engage the edge of the treadle when the trap is set, the treadle being urged upwardly by the spring 21 just enough to engage the lowermost extremity of the lug 32.

When the trigger is thus held by the treadle, the lug 31 will be enforced to keep its position in the detent 28.

The angular pull of the shaft against the trigger, due to the offset of the pivot, will force the lug 31 out of the detent 28 when the trigger is released by the treadle. The lateral resultant of force accomplishes this, and need be only sufficient to overcome the friction between the lug 31 and the shoulder of the detent 28, which is very small despite the considerable pull of the shaft.

The lateral force is decreased at the point of contact of the lug 32 with the treadle, due to the fact that the latter point is much farther from the pivot 30 than the lug 31. This extension of the trigger also brings the engagement of treadle and trigger nearer to

the hinge of the treadle, increasing the leverage of the treadle in releasing the trigger.

It will now be seen that depression of the treadle will release the lug 32, thus allowing 5 the pull of the shaft to force the lug 31 from the detent 28, and the trap will then snap shut.

Pulling the sliding jaw rearwardly causes 10 the member 16 to engage the arm 32^a, forcing the lug 31 into engagement with the detent and moving the lug 32 to position where the treadle may move upwardly to engage it.

In setting the trap, it is grasped by one 15 hand, the first two fingers straddling the treadle and engaging the respective elements 16, and the thumb hooked around the end of the base remote from the jaw 12. The other two fingers may then be placed against the side of the base, to steady the trap in the fingers.

20 By simply compressing the fingers toward the thumb, the trap may be set.

Some changes may be made in the construction and arrangement of the various parts of my invention, but it is my intention 25 to cover by my claims, any modified forms of structure or the use of mechanical equivalents, which may be reasonably included within their scope.

I claim as my invention:

30 1. An animal trap, comprising; a base including a jaw, a slidable jaw mounted on the base, a shaft secured to the slidable jaw and slidably supported by the base, a spring to urge the slidable jaw toward the other jaw, a 35 treadle hinged to the base, a trigger pivoted upon the base on an axis perpendicular to the longitudinal axis of the treadle and provided with an element to engage the shaft at a position spaced from the trigger pivot on a line 40 which crosses the shaft at an acute angle thereto, whereby the engagement of the said element and shaft is self-releasing, yet sustains a majority of the pull of the shaft under its spring pressure, and an element on 45 the trigger to engage the treadle, to secure the trigger against releasing the shaft, and in turn released by depression of the treadle.

2. An animal trap, comprising; a base including a jaw, a slidable jaw mounted on the 50 base, a spring to urge the slidable jaw toward the other jaw, a treadle hinged to the base, a trigger pivoted on the base on an axis perpendicular to the longitudinal axis of the treadle and provided with an element to engage a portion of the slidable jaw at a position 55 spaced from the trigger pivot on a line which crosses the axis of movement of the slidable jaw at an acute angle thereto, whereby the engagement of said element and 60 the slidable jaw is self-releasing, yet sustains a majority of the pull on the slidable jaw under its spring pressure, and an element on the trigger to engage the treadle, to secure 65 the trigger against releasing the slidable jaw,

and in turn released by depression of the treadle.

3. An animal trap comprising; a base including a jaw, a slidable jaw mounted on the base, a spring to urge the slidable jaw toward the other jaw, a treadle hinged to the base, a trigger pivoted on the base on an axis perpendicular to the longitudinal axis of the treadle and provided with an element to engage a portion of the slidable jaw, an element on the trigger to engage the treadle, to secure the engagement of trigger and slidable jaw, means to urge the treadle theretoward, and an arm on the trigger, extending into the path of movement of a portion of the slidable jaw, and actuated thereby to move both of said elements into engagement with their respective engaged members. 70

4. An animal trap comprising; a base including a jaw, a slidable jaw mounted on the base, a shaft secured to the slidable jaw and slidably supported by the base, a spring to urge the slidable jaw toward the other jaw, a treadle hinged to the base, a trigger pivoted to the base on an axis perpendicular to the longitudinal axis of the treadle and provided with an element to engage the shaft on one side, an element on said trigger to engage the treadle on the other side, means to urge the treadle toward the trigger, and an arm on the trigger, extending into the path of movement of a portion of the slidable jaw, and actuated thereby to move both of said elements into engagement with their respective engaged members. 75

5. An animal trap comprising; a base including a jaw, a slidable jaw mounted on the base, including a plate, a jaw formed at one end of the plate, finger engaging elements formed at the other end of the plate, extending at right angles thereto, and provided with guards extending parallel to each other, a shaft secured to the slidable jaw and slidably mounted on the base, a spring to urge the slidable jaw toward the other jaw, a treadle positioned between the shaft and the base, said shaft, treadle, and spring being received between said guards, and trigger mechanism for setting the trap. 80

6. An animal trap comprising; a base including a jaw, the edges of said base being bevelled toward each other and away from the jaw, a slidable jaw slidably mounted on the base, comprising a plate, fingers bent from the plate toward each other at approximately the same angle as the bevel on the base, so as to embrace the sides of the base, a spring to urge the slidable jaw toward the other jaw, and trigger means. 90

7. An animal trap comprising; a base including a jaw, a slidable jaw mounted on the base, a shaft secured to the jaw and slidably supported by the base, a spring to urge the slidable jaw toward the other jaw, a treadle hinged to the base between the shaft and the 100

base, a trigger pivoted to the base between the treadle and the shaft on an axis perpendicular to the longitudinal axis and provided with an element to engage the shaft at a position spaced from the trigger pivot on a line which crosses the axis of the shaft at an acute angle thereto, whereby the engagement of the said element with the shaft is self-releasing yet sustains a majority of the pull of the shaft 10 under its spring pressure, and an element on the trigger to engage the edge of the treadle, to secure the trigger against releasing the shaft, and in turn released by depression of the treadle.

15 8. An animal trap comprising: a base including a jaw, a slidable jaw slidably mounted on the base, a shaft secured to the slidable jaw and slidably supported by the base, a spring to urge the slidable jaw toward the 20 other jaw, a treadle hinged to the base, a bell crank shaped trigger pivoted to the base to move in a plane parallel thereto and adjacent said shaft, an element on said trigger to engage the shaft on one side, an element on said trigger to engage the treadle on the other side for holding the trigger in engagement with the shaft, said two elements being disposed on one arm of the trigger and the other arm being extended into the path of movement of a portion of the slidable jaw and actuated thereby to move both of said elements 25 into engagement with their respective engaged members.

Signed at Sioux City, in the county of 30 Woodbury and State of Iowa, this 24 day of August, 1928.
